S. MARCUS.
DOLL'S HEAD AND EYES THEREFOR.
APPLICATION FILED APR. 16, 1920.

1,373,439.

Patented Apr. 5, 1921.

Inventor
SAMUEL MARCUS
By his Attorney

Chas. C. Gill

UNITED STATES PATENT OFFICE.

SAMUEL MARCUS, OF BROOKLYN, NEW YORK, ASSIGNOR TO F. & M. NOVELTY CO., INC., OF NEW YORK, N. Y., A CORPORATION OF NEW YORK.

DOLL'S HEAD AND EYES THEREFOR.

1,373,439.

Specification of Letters Patent.

Patented Apr. 5, 1921.

Application filed April 16, 1920. Serial No. 374,258.

To all whom it may concern:

Be it known that I, SAMUEL MARCUS, a citizen of the United States, and a resident of Brooklyn, in the county of Kings and State of New York, have invented certain new and useful Improvements in Dolls' Heads and Eyes Therefor, of which the following is a specification.

The invention pertains to improvements 10 in the manufacture of the heads of dolls and also in the manufacture of artificial eyes for such heads, and the invention consists in the novel features hereinafter described, and particularly pointed out in the 15 claims. Considerable difficulty is met with in the proper securing of eyes in the heads of dolls and in the correct adjustment of such eyes to the eye-sockets in such heads, a part of the difficulty arising from the 20 fact that the dolls' heads, in respect of the eye-sockets, vary owing to the manner of manufacturing the heads and the material of which the heads are formed.

In accordance with my invention I provide a pair of eyes which are adjustable and support these eyes from a hanger secured within the head of the doll above the eyes, and in order to provide for the proper location, inclination and positioning of the 30 hanger and eyes I construct the inner forehead of the doll's head with a special seat adapted to receive said hanger and against which the hanger is secured by shellac or other cementitious material.

35 A further purpose of my invention is to furnish suitable means whereby glass eyes may be properly adjusted to and supported within the heads of dolls.

The invention and satisfactory means for 40 carrying the same into effect will be fully understood from the detailed description hereinafter presented, reference being had to the accompanying drawings, in which:

Figure 1 is a vertical section through the 45 face of a doll and eye mechanism embodying the essential features of my invention, the section through the eye mechanism being taken on the dotted line 1-1 of Fig. 2;

Fig. 2 is a front elevation of an eye-set 50 embodying my invention, the same being shown on a larger scale than that of Fig. 1 and as detached from the inner surface of the doll's head;

Fig. 3 is a vertical section through a por-

tion of the same, taken on the dotted line 55 3-3 of Fig. 2;

Fig. 4 is a vertical transverse section through the same, partly broken away, taken on the dotted line 4-4 of Fig. 3;

Fig. 5 is a horizontal section through a 60 portion of the same, taken on the dotted line 5-5 of Fig. 2;

Fig. 6 is a detached perspective view of a portion of the mechanism for securing one eye of the set to a bridge piece, a similar device being employed for securing the other eye to the bridge piece;

Fig. 7 is a transverse section corresponding with Fig. 4 illustrating a modified means for securing the eye to the end of a bridge 70 piece, the section being taken on the dotted line 7-7 of Fig. 8;

Fig. 8 is a top view of the same;

Fig. 9 is a top view corresponding with Fig. 8, but illustrating a further modification in means for securing a glass eye to the end of a bridge piece of a pair of eyes;

Fig. 10 is a vertical section through the same, taken on the dotted line 10-10 of Fig. 9;

Fig. 11 is a vertical section through the same, taken on the dotted line 11-11 of Fig. 9;

Fig. 12 is a detached perspective view of a portion of the securing means illustrated 85 in Figs. 9, 10 and 11, and

Fig. 13 is a horizontal section through a portion of the forehead of the doll, taken on the dotted line 13-13 of Fig. 1.

In the drawings, 15 indicates the face 90 portion of the head of a doll, and 16, 17, respectively, denote the right eye and left eye for the doll. The eyes 16, 17 are of substantially corresponding construction and are mounted on a bridge-piece 18 which is 95 suspended at the lower end of a plate or hanger 19 and supports a rod 20 on whose lower end is secured the customary weight 21.

At the inner surface of the forehead of the doll's face 15 is formed a downwardly 100 and inwardly inclined seat 22 at whose opposite edges are flanges 23. The seat 22 constitutes the only novel feature of the face of the doll, and this feature being located at the middle of the inner surface of the 105 forehead of the face and between the vertical planes of the eye-sockets of said face is one of great importance in enabling a work-

man to properly position the eye-set. The hanger 19 is a substantially flat plate, especially in its upper portions, and is secured by shellac or other suitable substance 24 5 against the seat 22 and between the flanges 23, said seat 22 compelling the hanger or plate 19 to take a downwardly and inwardly inclined position and the lower end of said plate being between the sockets for the eyes 10 16, 17.

The eyes 16, 17 are alike and each consists of a globular shell, preferably of glass, bearing at the front thereof a representation of the iris of the eye, and at the rear side there- 15 of a broken neck 25, which is incidental to the manufacture of the eye and performs no function so far as the present invention is concerned except that it affords a convenient handle by which the eye may be held 20 between the fingers during the adjustment of the eye angularly with respect to the securing means therefor hereinafter described.

The hanger 19 will preferably be formed of sheet metal, and in its upper portion it 25 has an opening 26, below which the hanger is formed with a loop 27 to clamp the legs of a bent spring 28 whose upper portion is within the outline of the opening 26, while the legs of the spring bear against the 30 bridge piece 18 in a direction to yieldingly press the eyes 16, 17 against the sockets in the face of the doll. The spring 28 is of considerable importance and need not be referred to in further detail at this place, since 35 said spring is illustrated in Letters Patent No. 1,331,272 granted to me on February 17, 1920. The lower opposite side edges of the hanger 19 are flanged forwardly, as at 29, and on said flanges are forwardly projecting 40 ears 30 containing elongated slots 31 through which the bridge-piece 18 passes and which, while said ears 30 serve to support the bridge-piece, permit said bridge-piece to have movement toward and from the face 45 of the doll under the control of the spring 28. The slots 31 are also shown in the aforesaid Letters Patent dated February 17, 1920.

The bridge-piece 18 may be formed from 50 a rod of wire, and from the central portion of this bridge-piece I suspend the rod 20 and weight 21, there preferably being a rigid connection between the bridge-piece and said rod and weight, so that the weight 55 may be depended on to turn the eyes 16, 17 in accordance with the inclination which may be given to the head of the doll, when desired.

With reference to the construction shown 60 in Figs. 1 to 6 inclusive, the eyes are secured to the ends of the bridge-piece by means of thin metallic bands 32 and sleeves 33, said sleeves being rigid with the bands 32 and receiving the ends of the bridge-piece 18, as 65 shown in Fig. 4. The bands 32 extend

around or encompass the eyes 16, 17 and are concave on their inner faces to snugly engage said eyes. The bands 32 are preferably in one integral strip, and at one end of the strip is formed a slot 34 to receive a tongue 70 35 formed on the other end of the strip. In applying the band to an eye, the band is bent around the eye and the tongue 35 inserted through the slot 34 and after the band has been drawn tightly around the eye, said 75 tongue is bent backwardly, as shown in Fig. 4, so that the band may very snugly hold the eye. The eye is of course adjusted angularly within the band 32 so that the iris of the eye may be correctly positioned. The 80 band 32 permits of the adjustment of the eye in all directions and forms in effect a universal joint connection between the eye and its securing means, and this is an important feature, because it is of the highest 85 consequence that the eye be correctly positioned with respect to the face of the doll regardless of irregularities that might be present in the head of the doll. The sleeves 33 are rigid with the bands 32 and these 90 sleeves while snugly fitting upon the ends of the bridge-piece 18 are also capable of angular movement thereon, and this likewise permits of a further adjustment of the eye after it has been secured within the band 32. 95 The sleeves 33 are slidable on the ends of the bridge-piece 18 and in consequence thereof the eyes may be adjusted toward and from each other at will to meet such conditions as may exist with respect to the face of the doll. 100 After the eyes have been properly spaced apart it is important that this spacing should be maintained, and as one means for securing the eyes both in their angular adjustments and in their spacing apart adjustments, I provide a stay-strip 36 which has a central aperture 37 so as to be strung on the weight rod 20 and finger portions 38 to extend through loops 39 slit in and pressed downwardly from the bands 32. 110 The eyes may be adjusted toward and from each other on the bridge-piece 18 and strip 36, and thereafter said eyes may be rigidly secured in their spacing apart adjustment by tightening the loops 39 against the strip 36 or bending the ends of the strip 36 downwardly so as to prevent sliding movement of the bands 32 thereon. The strip 36 is parallel with the bridge-piece 18 and becomes actuated by the rod 20 when the doll is reclined or turned upwardly from a reclining position, to suitably rotate or turn the eyes 16, 17 to closed and open position. The bands 32 closely engage the eyes 16, 17 and therefore the strip or the bar 36 when actuated by the movement of the rod 20 may, by acting through the bands 32, turn the eyes 16, 17 angularly, said eyes, bands 32, sleeves 33 and strip or bar 36 turning in unison.

The construction shown in Figs. 1 to 6 130

inclusive is a construction especially adapted to fragile glass eyes 16, 17 and avoids any necessity for drilling or otherwise breaking through the material of the eye-shells, and 5 said construction is of great importance in that it permits of a very wide range of adjustment of the eyes so as to adapt the eye-set, meaning thereby all of the mechanism shown in Fig. 2 to the heads of dolls varying in details or irregularities of construction. The downwardly and inwardly inclined seat is important in properly positioning the eye-set with respect to the inner surface of the doll's head and said seat not 10 only facilitates the application of the eye-set to the head of the doll, but prevents a workman, under ordinary conditions, from misplacing the eye-set when introducing the same to the head of the doll. The flanges 20 23 at the edges of the seat 22 snugly receive the edges of the hanger 19 and thus serve to compel or at least facilitate the securing of the hanger in proper vertical position, as distinguished from being inclined to one 25 side or the other within the doll's head.

In Figs. 7 and 8 I illustrate a modification of the invention and particularly in the matter of securing encompassing bands to the fragile eye-shells. In Figs. 7 and 8 I 30 number the eye-shell 40, the securing band 41, the bridge-piece 42 and the sleeve receiving the end of the bridge-piece, as 43, said sleeve being rigid with the band 41, and the shell 40 being the same as the shell 35 16 shown in Fig. 2. The band 41 does not extend completely around the shell 40, but is of metal and concaved on its inner surface and closely engages the shell 40. The ends of the band 41 are apertured and 40 drawn tightly around the shell 40 by means of a piece of wire 44 which is passed through the ends of the band and then has its ends twisted together, as shown, for the purpose of drawing the band closely around the 45 shell 40. The band 41 permits of the adjustment of the eye-shell the same as I have described with respect to Fig. 2. The sleeve 43 and bridge 42 correspond with the sleeve 33 and bridge 18 of Fig. 4 and will require 50 no special description. The securing band or strip 41 has a loop 45 formed therefrom to receive the end of a connecting and securing strip or bar 46, and the loop 45 and bar 46 correspond exactly with the 55 loop 39 and bar 36 shown in Figs. 1 to 6 inclusive. The modification presented in Figs. 7 and 8 therefore reside mainly in the means provided for tightening the securing band around the fragile eye 40, the wire 44 60 being a substitute for the slot 34 and tongue 35 shown in Fig. 6.

In Figs. 9 to 12 inclusive, which show a further modification of the invention, 47 designates the hollow eye-shell, 48 the securing 65 band, and 49 the bridge piece, said

bridge piece corresponding with the bridge piece 18 of Figs. 2 and 4. The band 48 is of thin sheet metal and is concaved on its inner face to snugly engage and encompass the shell 47, and the ends of said band at 70 the inner side of the shell are bent laterally to form fingers 50, 51, as shown in Fig. 12. The band 48 forms in effect a split ring having at the ends of the strip forming the band, the fingers 50, 51 which are utilized 75 by being squeezed toward each other for tightening the band around the shell 47. The fingers 50, 51 in the present instance extend over the end of the bridge-piece 49, as shown in Figs. 10 and 11, and within a 80 sleeve 52 applied on said fingers 50, 51 and which carries a screw 53 to engage the finger 51 and by pressing the same against the end of the bridge-piece serving to draw the upper side of the band 52 tightly against the 85 finger 50 and clamp said finger against the upper surface of the bridge-piece 49, as will be understood on reference to Figs. 10 and 11.

The construction shown in Figs. 9 to 12 90 inclusive is one permitting of all of the adjustments of the eye-shells hereinbefore described with respect to Figs. 1 to 6 inclusive, but since the shells become capable of being fixedly secured in their adjustments 95 on the ends of the bridge-piece by means of the screw 53, it is not necessary in the construction presented in Figs. 9 to 12 inclusive to make use of the auxiliary strip or bar 36 shown in Fig. 5, although said strip 100 or bar 36 may be made use of in the construction shown in Figs. 9 to 12 inclusive, if desired, for the purpose of facilitating the action of the rod 20 in turning the eyes in accordance with the inclination given to 105 the doll. In the construction shown in Figs. 1 to 6 inclusive, the screws 53 shown in Figs. 10 and 11 may be made use of if desired, and in that event the strip or bar 36 of Fig. 2 may be omitted. I prefer, however, to employ the strip or bar 36 in the construction shown in Fig. 2 so as to avoid the employment of the screws 53 shown in Figs. 10 and 11. If the sleeves 33, shown 110 in Figs. 2 and 4, are made to tightly fit 115 upon the ends of the bridge-piece 18, then neither the screws 53, nor the strip or bar 36 need be employed, but in that event somewhat more difficulty would be experienced in adjusting the eyes upon the ends of the 120 bridge-piece. I may add, also, that when the strip or bar 36 is made use of, the turning of the eyes may be accomplished therefrom in lieu of through the bridge-piece, and when the strip or bar 36 is made use 125 of and connected with the rod 20 so as to effect the turning or rolling action of the eyes, it is not necessary that the upper end of the rod 20 should be rigidly fastened to the bridge-piece, but even in such construc- 130

tion I prefer to secure the upper end of the rod 20 to the bridge-piece so that said rod may act through both the strip or bar 36 and the bridge-piece in rolling the eyes, the 5 ends of the bridge-piece then turning with the sleeves 33, during the rolling of the eyes, instead of said sleeves turning on the ends of said bridge-piece.

What I claim as my invention and desire 10 to secure by Letters-Patent, is:

1. An eye-set for dolls and the like comprising a pair of globular eye-shells bearing the representation of the iris, means connecting said shells comprising metallic bands 15 encompassing the shells and adapted to be closely secured thereto, means for preserving the alinement of said bands on the shells, and means for effecting the rolling of the eyes on the movement of the doll.

2. An eye-set for dolls and the like comprising a pair of globular eye-shells bearing the representation of the iris, a bridge extending between said shells, bands encompassing the shells and adapted to be closely 25 secured thereto and engaged with said bridge, means for securing the eyes within the head of the doll and means for effecting the rolling of the eyes on the movement of the doll.

3. An eye-set for dolls and the like comprising a pair of globular eye-shells bearing the representation of the iris, a bridge extending between said shells, bands encompassing the shells and adapted to be closely 35 secured thereto and engaged with said bridge, means for securing the eyes within the head of the doll and means for effecting the rolling of the eyes on the movement of the doll, said bands being concave on their 40 inner surfaces where they engage the eye-shells and having means whereby said bands may be closely drawn around the shells.

4. An eye-set for dolls and the like comprising a pair of globular eye-shells bearing 45 the representation of the iris, a bridge extending between said shells, bands encompassing the shells and adapted to be closely secured thereto and engaged with said bridge, means for securing the eyes within 50 the head of the doll and means for effecting the rolling of the eyes on the movement of the doll, said bands having rigid therewith sleeves engaging and adjustable on said bridge.

5. An eye-set for dolls and the like comprising a pair of globular eye-shells bearing the representation of the iris, a bridge extending between said shells, bands encompassing the shells and adapted to be closely 60 secured thereto and engaged with said bridge, means for securing the eyes within the head of the doll and means for effecting the rolling of the eyes on the movement of the doll, said bands being flexible strips of 65 sheet metal which are concave on their in-

ner surfaces to match the convexity of the shells and having means at the ends of said strips for connecting said ends and drawing the strips tightly around said shells.

6. An eye-set for dolls and the like comprising a pair of globular eye-shells bearing the representation of the iris, a bridge extending between said shells, bands encompassing the shells and adapted to be closely secured thereto and engaged with said 70 bridge, means for securing the eyes within the head of the doll and means for effecting the rolling of the eyes on the movement of the doll, said bands being flexible strips of sheet metal concave on their inner surfaces 80 to closely engage the convexity of said shells and having at one end a slot and at the other end a tongue to be entered through said slot and turned backwardly therefrom for tightening the bands on and securing them to said 85 shells.

7. An eye-set for dolls and the like comprising a pair of globular eye-shells bearing the representation of the iris, a bridge extending between said shells, concave bands 90 encompassing the shells and formed of flexible strips adapted to be closely drawn around said shells, means for engaging said bands with the bridge, means for preserving the alinement of the shells and means for effecting 95 the rolling of the eyes on the movement of the doll.

8. An eye-set for dolls and the like comprising a pair of globular eye-shells bearing the representation of the iris, a bridge extending between said shells, bands encompassing the shells and adapted to be closely secured thereto and engaged with said bridge, a strip connecting said bands, and means for effecting the rolling of the eyes 100 on the movement of the doll.

9. An eye-set for dolls and the like comprising a pair of globular eye-shells bearing the representation of the iris, a bridge extending between said shells, bands encompassing the shells and adapted to be closely secured thereto and engaged with said bridge, a strip connecting said bands, and means for effecting the rolling of the eyes on the movement of the doll and comprising a 110 weight-rod hanging from said bridge and connected with said strip and having on its lower end a weight.

10. An eye-set for dolls and the like comprising a pair of globular eye-shells bearing the representation of the iris, a bridge extending between said shells, a hanger suspending said bridge, bands encompassing the shells and adapted to be closely secured thereto and having sleeves which are adjustable on said bridge, a strip connecting said bands, and means for effecting the rolling of the eyes on the movement of the doll.

11. An eye-set for dolls and the like comprising a pair of globular eye-shells bear- 130

- ing the representation of the iris, a bridge extending between said shells, bands encompassing the shells and engaged with said bridge, and means for securing the eyes 5 within the head of the doll, said bands being concave on their inner surfaces where they engage the eye-shells and having means whereby said bands may be closely drawn around the shells.
- 10 12. An eye-set for dolls and the like comprising a pair of globular eye-shells bearing the representation of the iris, a bridge extending between said shells, bands encompassing the shells and adapted to be 15 closely secured thereto and engaged with
13. An eye-set for dolls and the like comprising a pair of globular eye-shells bearing the representation of the iris, a bridge 20 extending between said shells, a hanger suspending said bridge, bands encompassing the shells and adapted to be closely secured thereto and having sleeves which are adjustable on said bridge and a strip connect- 25 ing said bands.

Signed at New York city, in the county of New York and State of New York, this 14th day of April, A. D. 1920.

SAMUEL MARCUS.
